FIG. 1

FIG. 2

FIG. 3

INVENTOR

Will Schuld

BY
Milton S. Grindall
ATTORNEY

UNITED STATES PATENT OFFICE.

62 WILL SCHULDT, OF ARLINGTON TOWNSHIP, WOODBURY COUNTY, IOWA.

TIRE-TUBE CONTAINER.

1,378,905.

Specification of Letters Patent. Patented May 24, 1921.

Application filed December 19, 1919. Serial No. 346,109.

To all whom it may concern:

Be it known that I, WILL SCHULDT, a citizen of the United States, and a resident of Arlington township, in the county of Woodbury and State of Iowa, have invented certain new and useful Improvements in Tire-Tube Containers, of which the following is a specification.

My invention has for its primary object, 10 the production of a container for a pneumatic tire-tube, so constructed that an extra tube may be carried in a vehicle without danger of its being injured by abrasion with itself or the container walls, or otherwise injured.

A further object of the invention is the production of a container for a pneumatic tire-tube, simple and inexpensive in construction, and so constructed that a tire-tube 20 may be folded and placed therein, and then slightly inflated to prevent abrasion of the tube due to vibration.

A further object of the invention is the production of a container adapted to receive the usual folded tire-tube, and having a closure held normally secure against accidental displacement when the tube is inflated.

These and other objects and advantages I attain in the structure hereinafter described, 30 defined in the appended claims, and illustrated in the accompanying drawings, which form a part of this application, and in which like characters of reference indicate corresponding parts throughout the several views, 35 of which,—

Figure 1 is a plan of a container constructed in accordance with the invention;

Fig. 2 is a side elevation thereof with a tire-tube therewithin, parts being cut away, 40 and

Fig. 3 is a transverse vertical section thereof, taken on the line 3—3 of Fig. 2.

Although I have illustrated, and herein-after described but one embodiment suitable 45 for practising the invention, I would not be understood as being limited to the specific structure chosen for illustration, for many alterations and modifications may be made in the details of construction and arrangement 50 of parts herein disclosed, without departing from the spirit and scope of the invention, as defined in the appended claims.

Referring now to the illustrations, my device consists, preferably, of a rectangular 55 sheet-metal box including side walls, 4, end walls, 5, and a bottom, 6, the upper side be-

ing open and normally closed by a cover sheet, 7, adapted to fit between the walls, 4 and 5, and having upwardly extending side and end flanges, 8, and 9, which fit against the walls, 4 and 5, respectively. The side walls, 4, are provided with apertures, 10, each registering with the corresponding aperture of the other side; and the cover flanges, 8, are provided with apertures, 11, 65 which normally register with the apertures, 10. Through the side apertures, pass pins or bolts, 12, the portions of the pins penetrating one of the walls, being preferably notched, as at, 13, (Fig. 2), to prevent accidental displacement of the pins, as will presently appear.

14 represents the usual tire-tube as folded within the container and provided with the usual threaded valve-tube, 15, which extends 75 through one wall of the tire-tube and is provided on its inner end with the head, 16, positioned within the tube; and 17, represents the usual concavo-convex plate carried by the valve tube, and positioned adjacent the tire-tube.

The bottom, 6, of the container, I provide, therefore, with an intermediate transverse concavo-convex portion, 18, which approximately conforms to the plate, 17, and serves 85 as a seat therefor, the said portion, 18, being provided with an opening, 19, through which the valve-tube protrudes. The usual valve-tube-nut, 20, is then screwed onto the valve-tube, and into engagement with the 90 bottom of the container, 6, which prevents inward movement of the valve-tube. The tire-tube may then be sufficiently inflated to expand and substantially fill the container 95 to prevent abrasion of the tire-tube with itself or with the walls or cover of the container.

Referring to Fig. 3, it is clear that as the cover is carried upwardly by inflation of the tire-tube, the notched portions of the pins, 12, will be engaged with the adjacent portions of the wall, 4, above the apertures, 10, to prevent accidental displacement of the pins, yet to permit withdrawal of the pins, it is only necessary to depress the cover. 105

The valve-tube may be inclosed by the usual valve-tube-cap, 21, threaded upon the nut, 20.

Having thus described my invention, what I claim as new and desire to secure by Letters Patent of the United States is,—

1. A container for pneumatic tire-tubes

- having valve-tubes, including a walled inclosure having an opening through which a tire-tube may be introduced into the inclosure, a closure for the opening, a wall of said inclosure having an opening through which the valve-tube may be extended, whereby the tube may be inflated from the exterior of the inclosure, opposite walls of the inclosure being provided with registering apertures above the closure, cross pins removably-inserted in the apertures to prevent displacement of the closure when the tire-tube is inflated.
2. A container for pneumatic tire-tubes having valve-tubes, including a walled inclosure having an opening through which a tire-tube may be introduced into the in-

closure, a closure for the opening, a wall of said inclosure having an opening through which the valve-tube may be extended, whereby the tube may be inflated from the exterior of the inclosure, opposite walls of the inclosure being provided with registering apertures above the closure, cross pins removably-inserted in the apertures to prevent displacement of the closure when the tire-tube is inflated, and shoulders on the pins engageable with a wall of the inclosure when the tire-tube is inflated, to prevent accidental displacement of the pins from the apertures.

In testimony whereof I have hereunto set my hand this 15th day of December, 1919.

WILL SCHULDT.
